(57) **CLAIM**

The ornamental design for a support structure, as shown and
described.

DESCRIPTION

FIG. 1 is a top perspective view of a first embodiment for a
support structure in accordance with the new design;

FIG. 2 is a bottom right side perspective view thereof;

FIG. 3 is a bottom left side perspective view thereof;

FIG. 4 is a front elevational view thereof;

FIG. 5 is a right side elevational view thereof;

FIG. 6 is a left side elevational view thereof;

FIG. 7 is a rear elevational view thereof;

FIG. 8 is a top view thereof;

FIG. 9 is a bottom view thereof; and,

FIG. 10 is an alternative embodiment of the support structure
having a symbolic break in width, which is the sole
difference between it and FIGS. 1-9.

The broken lines in the figures depict portions of the support
structure and form no part of the claimed design.

The long dash-short dash lines in the drawings represent a
boundary of the claimed design and form no part of the
claimed design.

FIG. 10 is shown with a symbolic break in the width of the
claim. The break lines and any portion of the article between
the break lines forms no part of the claim.
